UNITED STATES PATENT OFFICE.

FREDERICK W. MITCHELL, OF CLEVELAND, OHIO.

PUMP FOR ELEVATING AND DISPENSING LIQUIDS.

Application filed May 9, 1925. Serial No. 29,069.

This invention relates to improved means for elevating and dispensing liquids, and in particular such means as are applicable to liquid delivered in small quantities, such as 5 applications of oils in various forms of the medical art, where local application is made in the oral and nasal cavities, and for local applications of insect solutions and dispensing perfumes or other volatile substances.

10 Another object of my invention is to provide a pumping means not subject to deterioration when exposed to contact with oil. At present rubber is necessary in the great majority if not all of the means of this character now in use.

15 Another object of the invention is to provide pumping means of this character, where wear is reduced to a minimum, and longer periods of maximum efficiency thereby obtained.

20 Another object of the invention is to provide a simple construction which may be used to dispense liquids from bottles and other small containers, and where the same pumping means may be used with new containers when the original is emptied, this being a 25 desirable feature, when the invention is used in connection with small bottles of medicinal toilet and sanitary solutions.

30 Another object of the invention is to provide a pump which will remain primed over long periods of nonuse, so that delivery of the liquid to be pumped will result from the first operation of the means.

35 Further objects and advantages of the invention are apparent from the following detailed description.

40 While the invention in its broader aspect, is capable of embodiment in various forms, a preferred embodiment thereof, and of the mechanism forming the same, are illustrated 45 in the accompanying drawings, in which:

Figure 1, is a cross sectional elevation of the device, taken along the line "BB" in Figure 2.

45 Figure 2, is a cross sectional elevation of the device taken along the line "AA" in Figure 1.

50 Figure 3, is a fragmentary section of the lower portion of the device showing an optional form of construction of a part thereof.

Figure 4 is an elevation of the device, with 55 portions broken away and in section.

Figure 5 is an elevation of the device, with 55 portions broken away and in section.

Referring to the drawings, 1, designates a container for the liquid to be dispensed, and with a liquid level indicated therein as at 2—2, (Fig. 1). Closing the top thereof, and fastened to the container, and in the present instance by threads, is a cover 3. A bent tube 4, is inserted thru the cover, and securely fastened to the inside of the bottom of the container. Projecting thru the cover 3, is also a piston rod 5^A, this piston rod being guided for vertical reciprocating movement in the cover, and being adjacent to, but external of the tube 4. A piston 5 is mounted in a suitable manner to the lower end of the piston rod, in Figures 1, 2, 4, and 5, this piston being shown as constructed of a solid metallic piece. The piston is bored centrally so as to sleeve over the tube 4, for vertical reciprocating movement therewith. Mounted over the piston, and for vertical reciprocating movement therewith is a tubular member 6. Mounted in a suitable manner, and fixed to the top of the piston 5, is a three pronged spring 7, the prongs of which are bent outward, so that they coat with the internal portion of the tubular member 6, and exert a frictional resistance therewith, which resistance must, it is evident, be overcome by energy applied to the piston rod 5^A, before the piston can be moved within the tubular member. Mounted over the tube 4, and fixed thereto is a stop plate 8, this stop plate being notched out on one side so as to permit of free reciprocating movement of the piston rod. Fastened to the lower portion of the tube 4, is a locating plate 9, this plate being adapted to hold the lower end of the tube 4, in a central relation internally of the container and to serve to seal the lower end of member 6.

The upper end of the piston rod 5^A is shown in the present instance looped over, to provide a grip for hand operation. The lower portion of the tube is sealed, in the present instance by a plug 4^B. A port 4^C is located at the lower end of the tube 4 this port being provided for access of liquid into the internal part of the tube as is herein-after disclosed. An optional method of constructing the piston is shown in Figure 3. In this optional construction the piston rod

5^a, is split at its lower end at two points, these split portions being bent outward so as to form a retainer for string. It is evident that by wrapping string about the piston rod and between the bent out portions of the rod 5^a, that a piston will result. It is also evident that the greater the amount of string wrapped in this manner, that the tighter the frictional resistance will be between the member 6 and the piston. The purpose of this frictional resistance is as hereinafter disclosed.

The operation of the device is as follows: Liquid to be dispensed is fed into the container 1, to some suitable level, such as 2—2 in the present instance. The cover 3, containing the pumping mechanism is then fastened to the top of the container. The piston rod 5^a, is then pulled in the upward direction of the arrow 10, (Fig. 4). The first portion of this upward travel of the piston rod will cause the tube 6, by virtue of its frictional contact with the piston 5, to also move upward, until its upward movement is stopped by reason of its upper end coming into contact with the stop plate 8. In this position of the tube member, when in contact with the plate 8, it is raised from contact with the plate 9, and a passage is thereby opened so that liquid is permitted to flow from the container to the tubular member 6. It is evident that with a stopping of the upward movement of the member 6, and upon a further movement upward of the piston, that liquid will be drawn from the container to the tubular member 6. This continuation of the upward travel of the piston is permitted by reason of the frictional resistance between the piston and the tubular member being overcome, by additional energy applied to the piston rod.

Upon a downward movement of the piston rod 5, in the direction of the arrow 12 (Fig. 5), the first portion of said downward movement will be utilized to return member 6 into contact with the plate 9, or into the position shown in Figure 1. Liquid previously drawn into the tubular member 6, by the upward stroke of the piston is now trapped between the plate 9 and the piston. Upon a continuation of the downward movement of the piston this liquid is then forced into the center of tube 4, thru the port 4^a, and discharged at the upper end of the tube 4, or elevated in said tube 4, until successive operations of the piston has elevated sufficient liquid to cause a delivery from end of tube 4.

It is evident that as the piston is elevated, and liquid is drawn from the container, to the tubular member 6, that with the port 4^a uncovered, liquid disposed from previous operations of the piston, in tube 4, will also tend to be withdrawn back into member 6. This condition how-

ever is substantially overcome by making the area of the port 4^a, much smaller than the area of the opening produced by elevating the member 6 into contact with the stop plate 8. With this difference in areas, a much greater amount of liquid will be drawn from the container, than from the tube 4, at each upward stroke of the piston, and it is then evident that the lowering of the piston will force this greater amount of liquid into tube 4, and that upon sufficient operation of the piston sufficient liquid will be elevated to cause delivery from upper end of tube 4. With the form of my invention it is also evident that tube 4 can be made of a sufficiently small diameter so that liquids forced therein will remain suspended by reason of capillary attraction and partial vacuum created by movement of materials heavier than air so that delivery under these conditions will become very efficient, but in any event I wish it understood, that it is only required that the port 4^a, be of sufficient smallness so as to partially serve the functions of a check valve, to effect delivery.

It is evident that upon a return of the piston to its lower position as shown in Figure 1, that port 4^a will be sealed against the liquid remaining disposed internally of the tube 4, and that the next subsequent operation of the piston will produce a delivery of liquid substantially equal to its displacement providing tube 4 is filled.

In pumps and liquid dispensers of this character it is customary to apply nozzles of varying types and designs, at the point of the pumping means where delivery occurs. However these being means common to the art to which my invention appertains, I have not shown or otherwise described same, as they form no part of my present invention.

I wish it understood, that the particular device and the different parts thereof illustrated and described, are merely typical embodiment of one form of my invention and that the specific construction described herein, is merely by way of illustration, as obviously a great many changes in construction and design can be made without departing from my invention. Also, various of the features described can be omitted, leaving the device operative to usefully do certain of the work described, and such changes are contemplated by me, and would not involve any departure from my invention.

Having thus described my invention, what I claim as new, and desire to secure by Letters Patent, is:

1. In combination, a receptacle having a discharge spout, a piston mounted on and surrounding the spout, a cylinder around the piston and movable relative thereto on interruption of the cylinder serving to

charge the cylinder or to eject the charge therefrom through the spout.

2. In combination, a receptacle having a discharge spout, a piston mounted on and surrounding the spout, a cylinder around the piston and movable relative thereto when on interruption of movement of the cylinder

serving to charge the cylinder or to eject the charge therefrom through the spout, the spout having an opening therein near the ¹⁰ bottom of the cylinder.

In testimony whereof I affix my signature.

FREDERICK W. MITCHELL.
